UNITED STATES PATENT OFFICE.

FRANK L. LINDSTROM, OF BRIDGEPORT, CONNECTICUT, ASSIGNOR TO THE LINDSTROM TOOL & TOY COMPANY, OF BRIDGEPORT, CONNECTICUT, A CORPORATION OF CONNECTICUT.

MECHANICAL TOY.

Application filed June 9, 1925. Serial No. 35,886.

The present invention relates to an improved mechanical toy, and more particularly a dancing figure toy in the form of a doll, animal, or the like, an object being 5 to provide such a device adapted to stand uprightly and operated in a manner to be vibrated or jiggled in simulation of a shimmy dance.

Another object is to provide such a device of extremely simple construction, and 10 preferably formed of sheet metal, as tin, pressed to shape, the device according to its present embodiment consisting of four 15 pressed metal pieces, a front and back and two feet members, and which are secured together by integral clamping lugs.

A further object is to provide a device in 20 which the motor is secured to one of the metal pieces only, and in which the set of the figure is such as to balance the motor during its vibratory operation in a manner 25 to maintain the figure in standing position.

A still further object is to provide a type 30 of figure adapted for direct ornamentation, as by painting, but which may, if desired, be provided with a fabric dress and an attached face portion of celluloid or other suitable material.

With the above and other objects in view, 35 embodiments of the invention are shown in the accompanying drawings, and these embodiments will be hereinafter more fully described, and the invention will be finally pointed out in the claims.

In the drawings:

Fig. 1 is a front elevation of a mechanical doll, according to one embodiment of the invention, having a fabric dress;

Fig. 2 is a vertical sectional view of an 40 embodiment, without the fabric dress, and showing the upper portion in side elevation;

Fig. 3 is a detail view of the vibratory motor employed;

Fig. 4 is a plan view of one of the foot 45 portions detached;

Fig. 5 is a front view of the leg end of the figure, without the foot attached; and

Fig. 6 is a detail sectional view, along the 50 line 6—6 of Fig. 2.

Similar reference characters indicate corresponding parts throughout the several figures of the drawings.

Referring to the drawings, and more particularly to Fig. 2 thereof, the device, according to the embodiment shown therein,

comprises front and back body portions 10 and 11 pressed to shape from sheet tin, or other suitable material, and having their meeting edges in a flat plane inclined slightly forward in the standing position of the 15 figure, as shown. At suitable points along these meeting edges there are provided integral projecting lugs 12, 13 and 14, two of these being on one edge in spaced relation, and the other being on the other edge and 20 disposed between the first two. These lugs are slightly offset from the outer surface of the body portions, as shown in Fig. 6, and by pressing the same down upon the outer surface of the opposed portions the same 25 are rigidly clamped together.

The lower ends of the body portions terminate in bifurcated leg portions 15 and 16, 30 annularly beaded as at 17, and provided upon the front and back edges with downwardly projecting pairs of spaced lugs 18 and 19. The two foot portions 20 are 35 pressed from sheet tin, or other suitable material, and are each provided with a flat outwardly projecting marginal flange 21 40 adapted to engage flatly upon the supporting surface upon which the figure is stood, the length of the feet and their spacing being such that the figure is firmly supported 45 against falling. Each foot is provided 45 near the heel with a circular aperture 22 50 provided with diametrically opposed lugs 23 and 24, and the same is assembled with the leg portion by engaging the beaded edge 55 of the latter with the upper surface of 55 the foot about the aperture 22, so that the lugs 18 and 19 at the front and rear engage 60 at each side of the lugs 23 and 24, the lugs 65 of the leg portion being bent outwardly 70 against the inner surface of the foot, while 75 the lugs of the foot are bent upwardly and 80 outwardly against the inner surface of the 85 leg portion, thereby securely and firmly 90 clamping the foot to the leg portion.

The spring motor unit, of clockwork type, 100 includes a sheet metal frame 25 provided with integral lugs 26 adapted to be engaged through holes 27 in the back body portion 11 and bent over to secure the motor unit 105 upon the inner side of said portion. The motor is provided with a winding handle or key 28 extended through a hole 29 in the portion 11 and adapted to be turned to wind the spring 30, which through suitable gears 31, 32 and 33 rotates a shaft 34 mounted in 110

the motor frame and depending substantially vertically therefrom, the axis of this shaft being parallel to the tilt of the figure, and upon the end of said shaft there is secured an eccentric or unbalanced weight 35.

It will be noted that the weight is below the center of gravity, which in combination with the forward tilting of the figure and the support of the motor upon the back body portion, tends to balance the figure, so that it is firmly supported on the feet, and even with excessive vibration, and turning movement, will not fall over.

In operation the rotation of the eccentric weight produces a vibratory or jiggling movement in the figure, which closely imitates a shimmy dance, the figure at the same time executing a pivoting or turning movement due to gyroscopic forces set up by the weighted motor shaft, this movement being in the same direction as the direction of rotation of said weight while the motor is running fast and being in the opposite direction when the motor is running slow.

As shown in Figure 1 the figure is provided with a fabric dress 36 including a hood 37 in the opening of which a face portion 38 of celluloid or the like is secured by sewing, the head thus formed being supported by the head portion of the metal body. It is obvious that the form of the device may be varied to represent numerous figures, as dancing dolls, clowns, monkeys, Teddy bears, and the like.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:

1. In a toy of the character described, a hollow figure including sheet metal front and back portions having their meeting edges in a substantially flat plane, and securing means comprising a plurality of groups of three lugs, two of said lugs being formed integrally in spaced relation upon the edge of one portion and the other lug being formed integrally upon the edge of the other portion and disposed between said lugs, said lugs being clamped upon the opposed portions to secure them together, sheet metal feet portions, and cooperating lugs on said front and back portions and said feet portions adapted to secure the latter to the front and back portions, and a vibratory motor supported within said figure.

2. In a doll, a body formed of a pair of hollowed sheet metal sections secured together with their edges in abutting relation, sheet metal feet sections, interlocking lugs carried by the sections and feet and bent against the opposed parts for securing the feet to the sections.

3. In a doll, a body formed of a pair of hollowed sheet metal sections secured together with their edges in abutting relation, sheet metal feet sections, means for securing said feet to said sections, said means comprising spaced lugs on the feet, spaced pairs of lugs on the body sections, and said lugs bent against opposed parts.

Signed at Bridgeport in the county of Fairfield and State of Connecticut, June, A. D., 1925.
